LIGHTING FIXTURE FOR BATHROOM CABINETS OR THE LIKE

Joseph Donald Willis, 301 E. Lawrence Road,
Phoenix, Ariz.

Filed Mar. 25, 1959, Ser. No. 55,172

Term of patent 14 years

(Cl. D48—20)

Fig. 1.

Fig. 2.

Figure 1 is a perspective view of a lighting fixture for bathroom cabinets or the like showing my new design; and

The dominant feature of my design resides in the portions shown in full lines.

I claim:

The ornamental design for a lighting fixture for bathroom cabinets or the like, as shown and described.
